UNITED STATES PATENT OFFICE.

EDWARD L. DUNN, OF EAST ORANGE, NEW JERSEY, ASSIGNOR TO OTIS ELEVATOR COMPANY, OF JERSEY CITY, NEW JERSEY, A CORPORATION OF NEW JERSEY.

FLOOR-CONTROLLER SYSTEM FOR ELECTRIC ELEVATORS.

Application filed March 10, 1923. Serial No. 624,101.

To all whom it may concern:

Be it known that I, EDWARD L. DUNN, a citizen of the United States, residing at East Orange, in the county of Essex and 5 State of New Jersey, have invented a new and useful Improvement in Floor-Controller Systems for Electric Elevators, of which the following is a specification.

My invention relates to control systems 10 for electric elevators and particularly to that part of automatic electric control systems by which an automatic stop is obtained at the desired floor landings.

In automatic electric control systems of 15 the push button operated type, one of the conventional arrangement for obtaining automatic stops of the car at the desired floors comprises what is known as a floor controller driven by the elevator hoisting 20 machine. The degree of accuracy of the stop of the car with the desired floor landings obtained by that arrangement is subject to the stretch of the driving ropes and, in the case of the traction type machine, to 25 the slip and creep of the driving ropes in addition. It is the object of my invention to overcome those difficulties by providing a floor stop switching mechanism, comprising two switches at each floor landing, each 30 switch adjustable independently, one for up and the other for down stop of the car at the floor landings. The switching mechanism is contained in its respective box together with the floor magnet switch. This 35 arrangement eliminates the trouble resulting from stretch, slip or creep of the driving ropes and also reduces to a minimum the hatchway wiring required.

Figure 1 shows a vertical plan view of 40 the inside of the floor stop switch.

Figure 2 is a side view of the same.

Figure 3 shows a perspective view of the adjustable contact segment cam.

Figure 4 shows a wiring diagram of an 45 automatic push button control system incorporating the floor stop switches.

Figure 5 shows the cams on the car to 50 operate floor stop switches and indicates the arrangement of mounting the various floor stop switches.

Referring to Figures 1 and 2, the floor 55 stop switch consists of a case 1 with cover 1' in which is mounted the floor magnet switch 2 with coil 3 and contact 4, the floor

stop contacts 5, 6 and 7, the cam segments 55 8 and 9 for connecting these contacts and the parts for moving these cams by movement of roller 10 as more fully described below. The magnet switch 2 is mounted on insulating block 11 by bracket 12. The stationary part of contact 4 is also mounted on insulating block 11 by contact holder 13. Contacts 5, 6 and 7 are also mounted on this same insulating block 11. This block 11 is attached to switch case 1 by screws 14. 60 Roller 10 is rotatably mounted on pin 15, the latter being rigidly connected by screws 16 to upper end of arm 17. The lower end of arm 17 is rigidly connected to shaft 18 by pin 19, this shaft being journaled in bearings 20 in switch case. Insulation bracket 21 is rigidly fastened by pin 22 to shaft 18 between bearings 20. Attached to bracket 21 is contact segment insulator 23. On this insulator is mounted contact segment support 24, and attached to this support by bolts 27, 28, 29 and 30 are contact segment cams 8 and 9, shown more in detail in Figure 3. Contact segments 8 and 9 contain slots 25 and 26 and can be rotated around 70 their supporting bolts 27 and 29 within the limits of these slots. The fixed position of these segments is determined by clamping bolts 27, 28, 29 and 30.

In the lower part of switch case 1 are 75 mounted two studs 31 and 32, each provided with a lock nut. These studs are adjustable and act as stops for insulation bracket 21. Since this bracket is rigidly connected to roller arm 17 carrying roller 10, these studs 80 31 and 32 act as stops for roller in either extreme position. No spring is used to maintain the roller in extreme position, the action of gravity being relied upon.

Figure 5 shows the cams used to operate 85 the floor stop switches and a diagrammatic arrangement of the floor stop switches 33, 34 and 35 for three floors. It will be noted that a slot cam, which for descriptive purposes may be called two cams 36 and 37, is 90 mounted on the car C in such a way that the floor switch roller will be operated from one side to the other as the car passes any landing. When the car stops at any landing, the roller will be held in the center 95 position. The wiring diagram shown in Figure 4 corresponds to arrangement of floor switches shown in Figure 5. While 100 105

this diagram is shown for three floors, the same arrangement may be used for any number of floors.

Figures 4 and 5 show the elevator car at rest at the second floor. It will be noted that under these conditions the roller 10 on floor stop switch 34 is held in its central position by cams 36 and 37; also that contacts in floor stop switch 34 are all open as are also the reversing switch contacts 38, 39, 40 and 41. This means that there is no current on motor M nor in brake magnet B at this time.

Assume that it is desired to bring the car to the first floor. The closing of push button 44 at first floor landing will cause the car to run down, the circuits being as follows: the initial circuit will be from the minus line through wires 45 and 46 to push button 44, wire 47, floor switch coil 3, in switch 35, and wires 48 and 49 to plus line. Coil 3 will then operate floor switch 2 and the latter will close its contact 4. This establishes circuit for the reversing switch as follows: minus line, wire 50, down-reversing switch coil RD, wire 51 and 52 to contact 5 on floor switch, contact segment 8, contact segment support 24, contact segment 9, contact 6, wire 53, contact 4, wires 54 and 47, floor switch coil 3, wires 48 and 49 to plus line. This latter circuit becomes self-holding and is independent of the push button 44. The reversing switch coil RD will close contacts 38 and 39 and motor and brake will be energized in the regular way. The elevator car will then run down. As the car approaches the lower floor, cam 36 on car C will engage roller 10 on switch 35. As the car moves down from the point of engagement, the roller 10 will be moved toward the right. This movement of roller 10 will move contact segment 8, contact segment support 24, and contact segment 9 toward the right. When this motion is sufficient to cause contact segment 8 to leave contact 5, the circuit to the reversing switch coil RD and floor switch coil 3 will be broken, the reversing switch will open its contacts and the motor will be stopped in the usual way. The exact point of car travel at which contact segment 8 will leave contact 5 can be adjusted to suit the conditions required by means of slot 25 and bolts 27 and 28.

When the car has stopped at the lower floor, the roller 10 on switch 35 will be held in central position by cams 36 and 37 on car as indicated in Figure 5 for a car stop at second floor. When the car moved down from the second floor the action of cams 36 and 37 on roller 10 of switch 34 moved this roller to its extreme right hand position resulting in contacts 6 and 7 in switch 34 being bridged by contact cam 8, contact support 24, and contact cam 9 on same

switch. This leaves floor stop switch 34 in the same position as Figure 4 shows switch 33, both switches being in position for an up operation of the car.

The above description of the operation of the elevator car is for a trip from the second to the first floor by the operation of the push button at the first floor landing. The same operation would be obtained by using push button 57 in car. The same operation would be obtained in running the car from any floor to any other floor except of course that different push buttons and floor stop switches corresponding to the various floors would come into play. When the operation is such that intermediate floors are passed, the cams 36 and 37 on the car will engage the roller on floor stop switches at the intermediate floors, moving these rollers from left to right or vice versa depending upon the direction of motion of the car. This movement of the floor stop switch roller will not open any energized circuits as the floor switch magnet energized for any particular operation is only that one located in the floor stop switch corresponding to the destination of the car. This movement of the rollers will however close the necessary circuits in the floor stop switch at any intermediate floor to enable subsequent operation to that particular floor.

Referring to Figure 5 it will be noted that the upper end of cam 36 and the lower end of cam 37 has a definite flare 36' and 37'. The purpose of this peculiar shape of cam is to prevent breaking and to reset the roller arm of floor stop switch when car passes intermediate floors, if for any reason the roller is reversed from its correct position. Assume that the car is traveling up. The rollers on all floor stop switches above the car should be in the extreme right hand position. Should any one of these rollers be in any other position due to tampering or some other reason, the flare on the upper end of the cam 36 will strike this roller as car approaches that particular floor and this roller will be moved first to right and then to left as car passes the floor and will remain in normal left hand position after car has passed floor. If cam 36 were not shaped as shown, an incorrect position of roller on floor stop switch might result in a breakage of floor stop switch parts as car passes an intermediate floor. The same condition can exist for the downward motion of the car and in this case the lower end of cam 37 will come into play.

The application of the floor stop switch as given above is for the simplest condition of an automatic push button control system. The addition of any of the well-known non-interference, self-holding, retiring cam door locking or safety circuits ordinarily used in

automatic push button control systems, to the circuits shown, will not change my invention in any way and any such circuits have therefore been omitted.

5 What I claim and desire to secure by Letters Patent of the United States is:

1. In an elevator control system, the combination with a switch mechanism located in proximity to a landing, said switch mechanism comprising a member pivotally mounted below its center of gravity to bias it to either of two positions, one on either side of a vertical plane through the pivot, and contacts adapted to be closed by said

10 member upon its movement to either of said two positions; of the elevator car and means carried thereby and co-operating with said member to hold it in neutral position and maintain said contacts open when said elevator car is at said landing.

15 2. In an elevator control system, the combination with a switch mechanism comprising a member pivotally mounted below its center of gravity to bias it to either of two positions, one on either side of a vertical plane through the pivot, and contacts adapted to be closed by said member upon its movement to either of said two positions; of the elevator car and an open slot cam carried thereby and co-operating with said member to move it from one of its contacting positions to the other upon movement of said car by the landing.

20 3. In an elevator control system, the combination with a switch mechanism comprising a member pivotally mounted below its center of gravity to bias it to either of two positions, one on either side of a vertical plane through the pivot, and contacts adapted to be closed by said member upon its movement to either of said two positions; of the elevator car and an open slot cam carried thereby and co-operating with said member to move it from one of its contacting positions to the other upon movement of said car by the landing.

25 4. In an elevator control system, the combination with a switch mechanism comprising a member pivotally mounted below its center of gravity to bias it to either of two positions, one on either side of a vertical plane through the pivot, and contacts adapted to be closed by said member upon its movement to either of said two positions; of the elevator car and an open slot cam carried thereby and co-operating with said member

to move it from one of its contacting positions to the other upon movement of said car by the landing, said cam having at its ends flared camming surfaces, one on either side of the slot, for returning said member to its proper location in the event of it being inadvertently displaced therefrom.

50 5. In the controller art of automatic electric elevators, an electric switching mechanism at each landing, comprising two contacts and a magnet floor switch, said magnet switch arranged to be in circuit with one of said contacts while elevator car is in operation.

55 6. In the controller art of automatic electric elevators, an electric switching mechanism at each landing comprising two contacts, a magnet switch and a contact operated by said magnet switch, said magnet switch and its contacts arranged to be in circuit with one of the two first mentioned contacts while the elevator car is in operation.

60 7. In the controller art of automatic electric elevators, the combination of an electric switching mechanism comprising a rocking adjustable contact part and two contacts, the contact part being adapted to be rocked to make contact with either of said contacts, and a third contact adapted to be continuously in contact with said contacts part.

65 8. In the controller art of automatic electric elevators, the combination of an electric switching mechanism comprising a rocking adjustable contact segment and adjustable stops therefor and two contacts, said contact segment adapted to be rocked to make contact with said contacts, and a third contact 70 flexibly contacting with said segment in all its positions.

In testimony whereof, I have signed my name to this specification.

EDWARD L. DUNN.
